UNITED STATES PATENT OFFICE.

HARRY H. CULMER, OF CHICAGO, ILLINOIS.

PROCESS OF COKING COAL.

Application filed January 19, 1920. Serial No. 352,309.

My invention relates to improvements in the process of coking coal and refers more particularly to a process in which the coal charge in the coking oven is vented to allow the heat of the oven to permeate more quickly into the body of the coal, at the same time allowing a free circulation and escape of the tars and gaseous vapors produced, also reducing the time necessary for the completion of the process as compared with former processes and producing a more uniform product.

Among its salient objects are to provide a process in which the coal charge in the coking oven is vented longitudinally, laterally or in both directions to permit the oven heat to reach the body of the coal more quickly; to provide a means of venting the coal charge so that the venting means will not interfere with the removable coke after the completion of the process; to provide a process in which the tar and gases driven off from the coal charge by the heat are allowed to escape through the vents in the coal, obviating the difficulties encountered with an almost impervious zone of tar and pitch.

Other objects of the present invention are to provide a process in which the moisture, tar and gaseous vapors are permitted free egress at all times during the coking of the coal so as not to disturb the bond of the coke at the time it is melting and setting together and preventing bubbles being blown in the plastic zone, causing porous coke; to provide a substance which is cheap and of such a nature that it effectually keeps open the ducts during the coking process in the presence of the high degree of heat to which it is subjected; to provide a process in which the coal is put into the furnace or oven in a plurality of combustible or carbonizable containers so that when the oven heat has reduced the container wall, there will remain a number of vents or ducts through the coal which permit the heat to penetrate quickly to the body of the coal; at the same time coking the coal into coke cubes substantially the size of the containers, thereby supplying a convenient size product and one that is very uniform in texture.

I have found that, in any type of oven or retort, there is produced in the coal charge a semi-solid mass during the period in which the oils and tars are liberated and

the following action takes place during the coking of the charge. The coal nearest to the heat cokes first, driving before it into the body of the uncoked coal, tar and other forms of liquid hydrocarbons. These liquid and semi-solid substances act as a flux, smelting down the coal into a plastic zone or wall. This sealing of the voids between the particles of coal does not allow the oils and gases to escape from the coking zone and causes the gaseous heating vapors to be drawn back through the hot coke. This plastic zone gradually backs away from the heat at the same time effectually sealing the heat from coming in contact with the fresh coal. The heat expended in this plastic wall retards the heat from attacking the fresh coal charge and accounts for the time necessary to complete the coking of the entire charge. Due to this zone of tar, intense heating has to be resorted to in order to coke the fresh coal behind the plastic zone or wall.

Occasionally steam, light oils and gases driven off in the heating of the coal will burst this plastic wall and cause the foamy or honeycomb structures therein. If these gases could escape without causing pressure against the incoming heat and proper means were provided for carrying off the oil, tar and gaseous vapors as they are formed, a stronger, firmer and more compact coke would result.

By arranging vents in the coal charge at intervals, the pressure caused by the steam and gaseous vapors confined in the untreated coal is allowed to escape and the heat of the furnace permitted to penetrate quickly to the body of the coal. The pressure produced in the untreated coal is caused by steam and gaseous vapors which the heat drives off from the coal while the tar zone is being formed. In this tar zone or plastic wall, the voids are cemented with tar and other forms of heavy hydrocarbons and these must be driven out by the heat and bubbles of gas and vapor passing through the plastic zone. It is this condition that is the main cause of spongy coke being formed. Ducts or vents of some nature are necessary whether the gases are taken from the body of the fresh coal or caused to escape back through the hot coke zone and by providing constant means of egress for the moisture, oil and tar vapors, quick access is given the heat to the untreated coal.

In experimenting with different kinds of vents, I have used iron pipes, hollow tile, perforated silicon tubes, asbestos wool, porous brick arches and like materials with but partial success, each having its objections, such as interference with the removal of the coke at the completion of the process, clogging of the ducts with carbon, the expense attached to the cleaning of the ducts and similar objections and inconveniences. Finally, I have discovered a cheap and effective method of accomplishing the desired result, and one which obviates the objections of cleaning, refitting and replacing tubes and ducts after each coking run.

In the drawings:—

Fig. 1 is a plan view of the straw mat before folding to form a container.

Fig. 2 is an edge view of the mat shown in Fig. 1.

Fig. 3 is a side view of the mat shown in Fig. 1, folded to form a container where a band is used for holding the upturned edges in place.

Fig. 4 is a top view of container shown in Fig. 3.

Fig. 5 is a side view of container where a staple is used for holding the upturned edges in place.

Fig. 6 is a perspective view of a block of stacked containers with coal therein.

Fig. 7 is a side view of coke oven with parts broken away, showing position of vent mats and core.

Fig. 8 is a plan view of cover for oven shown in Fig. 7.

Fig. 9 is a plan view of horizontal vent mat shown in Fig. 7.

Fig. 10 is a plan view of retort shown in Fig. 7.

Referring to the drawings, 1 designates a mat made of straw or other combustible substance held together by stitching shown at 2. The slots 3 are cut into the edges of the mat and together with the folding of the mat along the lines 4, provide a means of upturning the edges to form square containers, considered as a whole at 8, and shown in the succeeding Figures 3, 4, 5 and 6. To hold these upturned edges in place, bands 5 of fabric, paper or like material are placed around the perimeter of the container. Staples 6 may be used instead of the bands to hold the upturned portions in place. These containers are filled with ground coking coal and are stacked into a coking furnace or oven of any common type (not shown).

It may be necessary to alter the shape of the container to better fit the interior of the oven, but I have chosen to show a square container which may be conveniently stacked in a rectangular or square coking oven. When heat is applied to the oven, the coal in being reduced to coke gives off gase-

ous vapors and difficulty has constantly arisen in freeing the coal body of these oils, tars and vapors without producing an uneven texture in the coke. Also in coking, the coal will form a plastic wall in front of the heating zone, which retards to a great extent the action of the heat upon the untreated coal. To remedy this, I put the ground coal in a combustible container and stack the containers in the manner shown in Fig. 6 in the oven. When the heat of the oven begins to melt the coal, the gaseous vapors given off will seek the container walls, which will act as ducts or vents and will readily pass off as vapor. In this way I do away with the forming of a plastic wall and cause the heating gases to penetrate quickly to the body of the coal. Also due to the open vented portions produced by the container walls, the coke produced is of a very fine texture.

As the container walls are carbonized by the heating gases they tend to divide the coal body into blocks substantially the size of the containers. This aids materially in the removing of the coke from the oven in that the blocks will come out in separate units and may be stacked conveniently in bins or in waiting cars.

In Fig. 7 I show a form of oven which consists of a cylindrical retort 9 constructed of silica clay or like material, being provided with two cover portions 10 and 11, which are held in place by clamps 12 and 13 respectively. Clamping screws 14 secure the clamps and covers to flanges upon the cylindrical retort. A hole 15 in either end of the cover portions provides means for inserting the vent core 16 and are tapped to receive pipes 17 which lead to a condenser (not shown). These pipes 17 direct the vaporous by-products of the coal to the condenser. Flat mats 18 of straw or other combustible material are arranged at intervals within the retort. A hole 19 in the mat permits a threading of the combustible vent core therethrough. This retort is mounted in a fire box, the walls of which are fragmentarily shown at 20. The heating gases in the fire box reduce the coal in the retort, the heat penetrating from the outer surface of the retort toward the center core. The vapors and gas produced in the coal escape through the horizontal mats which extend to the inner surface of the retort. As the heat penetrates into the coal body, the gases and vapors which produce a semi-solid or plastic wall, work inwardly from the surface of the retort toward the combustible core.

It will be noted that the oils and vapors which combine to form this plastic wall do not produce an impenetrable mass, as the mats 18 furnish an outlet at all times for the generated vapors. As the heat works

inward, the coal at the outer part of the retort is coked and the mats are consumed or reduced. At all events they serve as a separating wall between the respective sections of the coal body. When the heating gases have finally consumed the central core and the coal body has been reduced to coke of a uniform texture, the covers of the retort may be taken off and the coke removed.

10 During the coking process, the vaporous by-products pass off through pipe 17 to any suitable condenser where they are collected.

I claim as my invention:—

1. A process for coking coal, comprising charging a coking oven with discrete masses of coal separated by a plurality of carbonizable but non-coking fillers, subjecting the charge to heat to cause carbonization of the coal and fillers, whereby the heated gases released from the coal may penetrate the body of the coal and escape through the vents produced by the carbonization of the fillers.
2. A process for coking coal, comprising charging a coking oven with discrete masses of coal separated by a plurality of carbonizable but non-coking fillers arranged in connected but spaced relation to each other in the coal charge, subjecting the charge to

heat to cause carbonization of the coal and fillers, whereby the heated gases released from the coal may penetrate the body of the coal and escape through the vents produced by the carbonization of the connected fillers.

35

3. A process for coking coal, comprising charging a coking oven with discrete masses of coal separated by a plurality of carbonizable but non-coking fillers arranged longitudinally and transversely in the coal charge, subjecting the contents of the coking oven to sufficient heat to carbonize the coal and fillers whereby the released gases may permeate the body of coal and pass through the vents produced by the carbonization and disintegration of the fillers.

40

4. A process for coking coal, comprising charging a closed retort with discrete masses of coal separated by a plurality of passages filled with a carbonizable but substantially non-coking material, subjecting the contents of the closed retort to sufficient external heat to carbonize the coal and carbonizable material whereby the released gases and vapors may permeate the coal body through the passages formed by the carbonization of the carbonizable materials.
